VARIABLE STROKE PUMP

Carl R. Seglund, Munising, Mich.

Application December 31, 1946, Serial No. 719,574

2 Claims. (Cl. 74—48)

1

This invention relates to variable stroke pumps, and more particularly to such pumps having one or more pistons or diaphragms and an adjustable device to vary the length of the stroke.

An object of this invention is to provide a simple, inexpensive and effective mechanism whereby the length of the stroke of the pump, and therefore its capacity or flow, may be altered while the pump is operating.

Further objects of this invention will become apparent from the following description when taken in conjunction with the accompanying drawings, the invention being particularly pointed out in the appended claims.

Reference is made to the drawings wherein like numerals of reference apply to the same parts throughout the several views, and wherein:

Figure 1 is a front elevation,

Figure 2 is an end elevation partly in section,

Figure 3 is a fragmentary top view, and

Figure 4 is a fragmentary front elevation indicating the connections to the pump.

Referring to the drawings in detail, in Figures 1 and 2, a driving shaft 10 is rotatably supported in bearings 11 of housing 12 and has attached to it an eccentric cam 13 operating in the longitudinal bearing slot 14 provided in an eccentric head 15 which is pivotally secured to crosshead 16 by means of bearing pin 17. At the opposite end of eccentric head 15 are provided one or more eccentric rods 18 attached by means of bearing pins 19 and arranged to impart suitable reciprocating motion to diaphragm or piston rod 20 and pump diaphragms or pistons 21, as shown in Figure 4.

Access to eccentric cam slot 14 is provided by means of a cap 22 which is shown secured in place by means of screws 23.

Crosshead 16 is slidably supported by the smooth portions of shaft 24. This shaft is rotatably supported in bearing brackets 25 secured to the casing 12 by means of bolts 26 and 27 and is provided with pinned collars 28 and 29 to retain it in proper position. It also has a portion 30 and 31 of its length adjacent each end threaded right and left handed, respectively, for operation in sliding nuts 32 and 33.

Nuts 32 and 33 may be separated along shaft 24 at any suitable distance apart, greater than the distance between the opposite faces of the upper portion of crosshead 16, by rotating the thumb wheel 34 in proper direction.

When sliding nuts 32 and 33 are positioned at a distance greater than the width between the faces of the crosshead 16 and a load is placed

upon the pump, it will be seen that the cross-head may freely reciprocate along shaft 24 throughout this greater distance whenever shaft 10 and eccentric cam 13 are rotated, and thus the eccentric head 15, enclosed by the bifurcated lower projection of crosshead 16 pivoting on pin 17, will cause a regulated motion to be applied to the eccentric rod 18 and eventually to the pump pistons or diaphragms 21. Thus, the length of the stroke and therefore the capacity of the pump may be readily altered while in operation without changing the driving speed of the eccentric shaft 10.

It is to be understood that various modifications and changes may be made in this invention without departing from the spirit and scope thereof as set forth in the appended claims.

What is claimed is:

1. In a variable stroke mechanism comprising a support, a rotary drive shaft journaled on the support and carrying an eccentric cam, an end-wise reciprocable rod disposed transversely of the driven shaft, and a downwardly-extending cam block pivotally connected at the lower portion thereof to the reciprocable rod and having an intermediate vertically-elongated opening forming a cam slot for the eccentric cam traversed by said drive shaft in effective position to engage the cam with the sides of the cam slot, a pair of abutment means spaced apart on the support and means for adjusting the relative distance between the two abutment means, the improvements which include a slideway on said support between said two abutment means disposed transversely of the drive shaft, a slidable block reciprocable and slidable on said slideway from one abutment means to the other, and a depending portion upon the slidable block pivotally connected to the upper end of said cam block to allow the latter to swing from said slidable block about a pivot axis parallel to said drive shaft in a direction from side to side relative to said slidable block to reciprocate said reciprocable rod during rotation of said drive shaft with consequent reciprocation of said slidable block along said slideway between the two abutment means.

2. In a variable stroke mechanism comprising a support, a rotary drive shaft journaled on the support and carrying an eccentric cam, an end-wise reciprocable rod disposed transversely of the driven shaft, and a downwardly-extending cam block pivotally connected at the lower portion thereof to the reciprocable rod and having an intermediate vertically-elongated opening forming a cam slot for the eccentric cam traversed by said

drive shaft in effective position to engage the cam with the sides of the cam slot, a pair of abutment means spaced apart on the support and means for adjusting the relative distance between the two abutment means, the improvements which include elongated guide means including a second shaft rotatably mounted on said support between the two abutment means, the second shaft having oppositely-threaded ends and an intermediate smooth portion, a thumb wheel fixed on one end of said second shaft for rotating the same at will, a pair of internally-threaded simultaneously-adjustable nuts mounted on the threaded ends of said second shaft and forming said two abutment means, a slidable block mounted on the second shaft and slidable upon the intermediate smooth portion thereof between said adjustable nuts from one nut to the other in a direction transverse to that of the axis of said drive shaft, depending lug means integral upon the lower portion of said slidable block, corresponding upwardly-extending lug means on the upper end of said cam block, and a pivot pin extending through both lug means in substantial parallelism to said drive shaft and transversely of said second shaft to allow the cam block to swing from said slide block about a pivot axis parallel to said drive shaft from side to side

relative to said slidable block in such fashion as to reciprocate said reciprocable rod during rotation of said drive shaft with consequent reciprocation of said slidable block along said smooth portion of said second shaft between the two adjusting nuts.

CARL R. SEGLUND.
